CLAIM

We claim the ornamental design for a outer segment of a disposable plate, as shown and described.

DESCRIPTION

FIG. 1 is a perspective view of an outer segment of a disposable plate, shown within the environment depicted in broken lines;

FIG. 2 is a perspective view of FIG. 1;

FIG. 3 is a top plan view of FIG. 1;

FIG. 4 is a side plan view of FIG. 1, the opposite side being a mirror image;

FIG. 5 is a bottom plan view of FIG. 1;

FIG. 6 is a front view of FIG. 1;

FIG. 7 is a rear view of FIG. 1; and,

FIG. 8 is a cross-sectional view of FIG. 2, taken along lines 8—8 of FIG. 2.

Broken lines in the drawings form no part of the present design.
